UNITED STATES PATENT OFFICE.

EUGENE R. PRUITT, OF BALTIMORE, MARYLAND.

HOT-WATER HEATING SYSTEM.

1,249,824.

Specification of Letters Patent. Patented Dec. 11, 1917.

Application filed February 14, 1917. Serial No. 143,474.

To all whom it may concern:

Be it known that I, EUGENE R. PRUITT, a citizen of the United States, residing at Baltimore, in the State of Maryland, have 5 invented certain new and useful Improvements in Hot-Water Heating Systems, of which the following is a specification.

This invention relates to improvements in hot-water heating systems, and has for its 10 object to provide a device which is simple in construction and efficient in operation, and which can readily be applied to any furnace, or heating plant.

The invention consists of the novel construction and arrangement of the parts and combination of parts hereinafter more fully set forth in the following specification and pointed out in detail in the appended claims.

In the accompanying drawings.—

20 Figure 1 is a side elevation of a furnace, partly broken away and showing my invention applied thereto.

Fig. 2 is an enlarged detail section of the pipes, the feeding and circulation of the water being indicated by the arrows.

Referring to the accompanying drawings, forming part of this specification, and in which like reference numerals designate like parts throughout the several views thereof, 30 1 designates the furnace in which the vertical pipe 2 is placed and which extends down into the fire box of said furnace. This pipe 2 is connected to and communicates with the pipe 3, which latter projects through the 35 furnace and has a pipe 4 connected to and communicating therewith, which said pipe 4 carries the heated water to the radiator 5, and the return water pipe 6 leading from the said radiator 5 to and communicating with the 40 pipe 3. The feed water pipe 7 is also connected to and communicates with the pipe 3. Said feed water pipe 7 passes around the furnace 1 and is connected with any source of supply, and may also be connected 45 to an expansion tank if desired. The pipe 3 is provided with a partition 8 between the supply pipe 7 and the pipe 4. Within the pipe 3 is a smaller pipe 9 which has one end projecting through said partition 8 adjacent 50 the supply or feed pipe 7 and the other end extending down into and terminating near the lower end of the pipe 2. The said pipe 2 is provided with a plug 10 in its lower end and a drain pipe 11.

55 The pipes described are for heating one

radiator and the same are duplicated for each radiator to be heated.

The operation of the device is as follows:

The pipe 2 is down in the fire-box of the furnace 1 and as the water flows from 60 the pipe 7 into the pipe 3 the latter being closed by the partition 8 the water will flow through the small pipe 9 down into the pipe 2 where it is heated and then up through pipe 3 to pipe 4 where it flows to the radiator 5. As the water cools it flows back 65 through the return pipe 6 to the pipe 3 on the opposite side of the partition 8 and then passes through the small pipe 9 to the pipe 2 where it is reheated and passes to the radiator 5.

Having thus described my invention, what I claim is:

1. The combination with a heater and a radiator, of a pipe projecting into the fire-box of said heater, a pipe connected to the first mentioned pipe and leading to the radiator, a pipe leading from the radiator to and communicating with the first-mentioned pipe, a supply pipe connected to said first-mentioned pipe, a partition in said first-mentioned pipe between the supply pipe and the pipe leading to the radiator, a small pipe within the first-mentioned pipe having 70 one end projecting through said partition 85 and the other end projecting down to near the bottom of the pipe in the fire-box.

2. The combination with a heater and a radiator, of a pipe projecting into the fire-box of said heater, a pipe connected to the 90 first-mentioned pipe and leading to the radiator, a pipe leading from the radiator to and communicating with the first-mentioned pipe, a supply pipe connected to said first-mentioned pipe between the pipe leading 95 to the radiator and the pipe leading from the radiator, a partition in said first-mentioned pipe between the supply pipe and the pipe leading to the radiator, and a small pipe within said first-mentioned pipe and 100 having one end projecting through said partition adjacent the supply pipe and the other end projecting down to near the bottom of the pipe in the fire-box.

In testimony whereof I affix my signature 105 in the presence of two witnesses.

EUGENE R. PRUITT.
